UNITED STATES PATENT OFFICE

158,836

GAME DEVICE

Raymond F. Brennan, Attleboro, Mass.

Application September 16, 1948, Serial No. 148,599

Term of patent 3½ years

(Cl. D34—5)

To all whom it may concern:

Be it known that I, Raymond F. Brennan, a citizen of the United States, residing at Attleboro, Commonwealth of Massachusetts, have invented a new, original, and ornamental Design for Game Device, of which the following is a specification, reference being had to the accompanying drawing, forming a part thereof.

Fig. 1 is an elevational view of a game device embodying my new design;

Fig. 2 is an elevational view of the device taken at right-angles to Fig. 1; and

Fig. 3 is an end view of the same.

I claim:

The ornamental design for a game device, substantially as shown.

RAYMOND F. BRENNAN.
